(57) **CLAIM**

The ornamental design for a socket mount, angle adjustable tool holder for extension poles, as shown and described.

DESCRIPTION

FIG. 1 is a front perspective view of a socket mount, angle adjustable tool holder for extension poles showing my new design.

FIG. 2 is a front elevational view thereof.

FIG. 3 is a side elevational view taken from the left of FIG. 2.

FIG. 4 is a rear elevational view taken from the opposite side of FIG. 2.

FIG. 5 is a side elevational view taken from the left of FIG. 4.

FIG. 6 is a top plan view taken from the top of FIG. 4; and, FIG. 7 is a bottom plan view taken from the bottom of FIG. 2.
